Primary Examiner — Marissa J Cash*Assistant Examiner* — William B Melliar(74) *Attorney, Agent, or Firm* — Minta Law Group LC;
Veronica-Adele R. Cao(57) **CLAIM**

The ornamental design for a pocket light with magnet, as shown and described.

DESCRIPTION

FIG. 1 is a top front perspective view of the pocket light with magnet, showing my new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view of the pocket light with magnet. The broken lines in FIG. 4 depict portions of the pocket light with magnet that form no part of the claimed design.
